Term of patent 14 years

(Cl. D61—1)

FIG.1

FIG.2

FIGURE 1 is a plan view of a motion picture film reel, showing our new design; and

FIGURE 2 is a side elevational view thereof.

Our design is characterized by planar spokes which spiral outwardly from a hub of the configuration disclosed, said spokes having their narrowest dimension adjacent said hub and their widest dimension adjacent the rim, all as shown.

We claim:

The ornamental design for a motion picture film reel, as shown and described.
